OUTSIDE PIPE CUTTER

Dempson H. Reed, Houston, Tex.

Application August 24, 1945, Serial No. 612,340

11 Claims. (Cl. 164—0.6)

1

The invention relates to an outside pipe-cutter of the compensating type so as to provide a graduated frictional drive to accomplish the cutting action.

The present pipe cutter is in the nature of an improvement over that shown in my prior patent, 2,213,049 issued August 27, 1940.

In the operation of an outside pipe-cutting tool in a well bore for the purpose of severing pipe great difficulty is encountered due to various conditions such as the particular position or inclination of the pipe, the hardness of the material of the pipe, and the fact that the tool must operate in a medium of drilling fluid or abrasive slush. An outside pipe-cutter in a majority of instances is used in cutting off sections of drill pipe which is usually made of high carbon steel having a relative thick wall so that it is difficult to cut and the tool must be operated in the annular space around the outside of the pipe being cut and within the confines of the diameter of the well bore or casing therein.

With the foregoing conditions in mind, it is obvious that an adjustment of the cutters for one set of circumstances may not cause the cutter to operate as effectively under other conditions and that a setting of the cutters before the tool is lowered into the well bore may differ as being an improper setting when the conditions down in the well are encountered. It is therefore desirable to provide a tool wherein the power tending to advance the cutters may be adjusted or varied, depending upon the conditions encountered, because a driving force which would advance the cutters at one location or against one portion of the pipe might be entirely inadequate when used in making another cut.

It is therefore one of the objects of the invention to provide an outside pipe-cutting tool wherein the frictional driving force tending to advance the cutters to perform the cutting action may be adjusted by manipulation of the tool while it is in position in the well bore.

Another object of the invention is to provide an outside pipe-cutting tool wherein the driving mechanism for advancing the cutters may be adjusted for increasing the driving force by manipulation of the tool in the well bore either before or during the cutting action.

Another object of the invention is to provide a driving mechanism for advancing the cutters in an outside pipe-cutting tool which can be adjusted by backing up the tool.

Still another object of the invention is to provide a compensating driving mechanism for out-

2

side pipe-cutters wherein the friction driving rings are so constructed as to be unaffected by the flow of flushing fluid.

Still another object of the invention is to provide an anchor device for outside pipe-cutting tools which may be operated to move into pipe engaging position by the application of hydraulic pressure.

Another object of the invention is to provide a control mechanism for advancing the outside pipe-cutters against the pipe said mechanism including a spring loaded compensating friction drive.

Other and further objects of the invention will be readily apparent when the following description is considered in connection with the accompanying drawings, wherein:

Fig. 1 shows the outside pipe-cutting tool in vertical elevation with one quarter cut away to illustrate an internal arrangement of the parts.

Fig. 2 is an enlarged sectional view of the pipe-cutter anchoring mechanism.

Fig. 3 is a transverse section through the tool illustrating the splined arrangement of the parts to effect rotation of one part with respect to the other.

Fig. 4 is a vertical sectional view illustrating the spring loaded compensating adjustment for the driving mechanism.

Fig. 5 is a section illustrating the ratchet dogs of the compensating driving mechanism.

Fig. 6 is a transverse section looking down on the construction of Fig. 5.

Fig. 7 is an enlarged detailed view illustrating the cutters as having severed the pipe.

Fig. 8 is a transverse sectional view through the tool looking down on the cutting members.

Fig. 9 is a broken away side elevation looking at the cutter member advancing mechanism.

In Fig. 1 the pipe or fish 2 which is to be severed is illustrated as a piece of heavy drill pipe having a coupling 3 thereon. For some reason or other this pipe 2 has become lodged or stuck in the well bore and cannot be removed. The outside pipe cutting tool 5 is thus being lowered over the pipe 2 with a view of severing the upper section 6 of the pipe from the lower portion 7 which is lodged in the hole.

This pipe cutting tool 5 is arranged to be lowered into the well bore and manipulated by an operating pipe 8 which is threaded at 9 into the body or housing of the tool 10. This housing is arranged to contain the various mechanisms of the cutting tool and at the upper end there are arranged a plurality of dogs or pipe engaging

members 11 which are mounted on a bushing 12 so as to seat on the shoulder 13 thereon. These dogs are normally pressed inwardly by a leaf spring 14 and have a tooth inclined edge 15 thereon to engage against the shoulder 16 of the coupling or tool joint 3.

The springs 14 normally urge these dogs or engaging members inwardly toward the pipe but they are enabled to move backwardly so as to snap by the collars 3 which are passed on the way down.

Fig. 1 shows this anchor mechanism as having been locked or latched in pipe engaging position by moving the flange 20 of the sleeve 21 in behind the upper end of the dogs. This is accomplished by the application of hydraulic pressure to the upper surface 22 of the sleeve 21. This sleeve is normally urged upwardly by the coiled spring 23 seated on the shelf 24 carried by the cylinder 25. This cylinder is in turn retained in position by the set screws 26 on the bushing 27 as best seen in the left hand side of Fig. 2. Normally the flange 20 will be spaced above the upper end of the dogs due to the force of the coil spring 23 so that the dogs can slip past the couplings 3. When it is desired to set the tool a pump pressure through the operating pipe 8 will be increased so that the resistance to flow downwardly through the tool will be applied to the surface 22 on the upper end of the sleeve 21. In this manner the flange 20 will move in behind the dogs to accomplish the locking thereof so that a subsequent upward pull on the tool to effect the cutting action will not dislodge the tool because the anchor mechanism will be securely locked.

This anchor mechanism, including the bushing 12, is supported on the anti-friction bearings 28 supported upon a rib 29 of the housing 10.

Threaded to the bushing 12 at 30 is the driving skirt 31 projecting below the rib 29. This driving skirt has an off-set 32 thereon which is arranged to have the set of friction rings 33 raised upwardly against its lower surface. These friction rings may be provided in any desired number and are offset in size and provided with transverse grooves or slots 36 as best seen in Fig. 4. These slots and offset sizes permit the flow of fluid past the rings in actual use so that there will be no building up of hydraulic pressure on the rings, which might interfere with the frictional resistance or drive as will be later explained. These rings are supported upon the shoulder 34 of the driving collar 35. This driving collar is movably arranged within the housing 10 and is threaded at 37 to a compensating ring 38 which rides on the surface 39 of the nipple 40 which is threaded at 41 to the housing 10. The nipple 40 has a plurality of upstanding pins 41' thereon best seen in Fig. 6 which are arranged to be received in the notch 42 of the pawl 43 which is hinged at 43' on the compensating ring 38.

In this manner when the housing 10 is rotated by the operating pipe 8, the pins or studs 41 will move in an accurate path beneath the pawls 43 while the compensating ring 38 is rotated with the housing at a slower rate, dependent upon the friction between the friction rings 33. The driving collar 35 due to the threads 37 will have a tendency to rotate with the compensating ring and in this manner the shoulder 34 will tend to carry the friction rings 33 around with it.

In order to vary the friction driving force imparted to the driving collar 35 by the friction

rings 33, the compensating rings 38 has an anti-friction bearing 43 thereon which supports a plurality of coil springs 44. These coil springs urge the ring 45 upwardly toward the shoulder 34. This ring 45 carries a plurality of studs 46 projecting through the openings 47 in the shoulder 34 bearing against the lower surface 48 of the lowermost one of the friction rings 33. In this manner there will be a spring loaded compressive force applied to the friction rings tending to compress them together and increase the frictional resistance to sliding. It seems obvious that by varying the vertical position of compensating ring 38 by relative turning between such ring and the pins 41 that the ring will be raised due to the threads 37. Any upward movement therefore will increase the compression on the springs 44 and consequently increase the frictional driving effect on the shoulder 34 and the driving skirt 35.

Fig. 3 shows every other one of the rings 33 as being provided with notches on the outer periphery to engage corresponding splines in the driving collar 35 while the alternate rings will be splined on the inside of the periphery to engage the driving skirt 31. In this manner half of the rings will be held stationary with the driving skirt and half of them will be compelled to move with the driving collar.

The driving collar 35 is splined into the driven member 50 which is threaded with a coarse thread 51 into the nipple 40. This member 50 is thus arranged for relative vertical movement due to these threads 51 but is compelled to rotate with the driving collar 35. If this assembly rotates as a unit, then the driven member 50 will not negotiate any vertical movement.

This driven member 50 has circumferentially spaced thereon the cross pins 52 upon which are mounted the links 53 for pivoting movement. These links are in turn pivoted at 54 with the cutters 55 which are carried in the cutter arm 56 pivoted at 57 in the housing 10 of the tool.

If the driven member 50 moves downwardly due to the relative turning between such member and the nipple 40, then a block portion 59 thereon is arranged to slide on the surface 60 on the cutter arm 56 so as to cause relative sliding movement from the position of Fig. 1 to the position of Fig. 7 when the cutter is fully advanced. The pin 54 has a flattened side or area 62 thereon as seen in Figs. 1 and 7 which serves to lock the cutter 55 against any tilting movement where it bears against the surface of the block 59.

The links 53 prevent the cutters from advancing more than the predetermined amount at which the driven member moves downwardly so as to prevent gouging of the pipe.

It seems obvious that with the foregoing construction, ready adjustment of the frictional driving action can be had because when the cut is started, and if the operator finds that the resistance to cutting is such that the cutters do not advance, it is only necessary for him to stop the clockwise rotation of the tool and back it up a desired amount so as to cause the pawls 43 to click over the pins or studs 41. This turning movement causes the threads 37 to move the compensating ring 38 upwardly which increases the compression on the springs 44 and moves the studs 46 against the friction rings with a greater force. The rotation of the tool in a clockwise direction can then be resumed and the friction tending to drive the driven member 50 has thus been increased. It seems obvious that the fric-

tional driving force can thus be adjusted to apply the desired force tending to advance the cutters to negotiate the cut 61 in the pipe 2.

Broadly the invention contemplates a compensating outside pipe-cutting tool where the frictional driving force tending to advance the cutters can be adjusted while the tool is in the well bore, depending upon the resistance encountered.

What is claimed is:

1. An outside pipe-cutting tool including a housing, means to anchor said housing against upward movement on the pipe being cut including means to contact the pipe, and means movable by the flow of liquid pressure in the tool to move said anchor means into firm biting engagement with the pipe.

2. An outside pipe-cutting tool including a housing, means to anchor said housing against upward movement on the pipe being cut including means to contact the pipe, lock means movable by the flow of liquid pressure in the tool to move said anchor means into engagement with the pipe, and spring means to release said lock upon reduction in the flow of liquid.

3. An outside pipe-cutting tool including a housing, means to anchor the tool against upward movement on the pipe, pipe cutting members in the housing, a friction driving means operable against said anchor means to advance said cutter to cut the pipe, including a plurality of friction rings.

4. An outside pipe-cutting tool including a housing, means to anchor the tool against upward movement on the pipe, pipe cutting members in the housing, a friction driving means operable against said anchor means to advance said cutter to cut the pipe, including a series of friction rings, and an additional means to adjust the frictional pressure of said rings to vary the driving force advancing said cutter.

5. An outside pipe-cutting tool including a housing, means to anchor the tool against upward movement on the pipe, pipe cutting members in the housing, a friction driving means operable against said anchor means to advance said cutter to cut the pipe, including a series of friction rings, and an additional means to adjust the frictional pressure of said rings to vary the driving force advancing said cutter by backing up the tool relative to said anchor means while such means is engaged.

6. An outside pipe-cutting tool including a housing, an anchor to engage the pipe being cut so as to position the tool, cutters in the housing, and a friction drive to advance said cutters including means to adjust such drive while the tool is in cutting position in the well.

7. An outside pipe-cutting tool cutter driving

construction including an anchor to engage the pipe, cutters to cut the pipe, and a friction drive between said anchor and cutters including a plurality of friction rings, a drive sleeve to be moved longitudinally by said rings to cause advance of the cutters, and means to adjust the frictional pressure on said rings.

8. An outside pipe-cutting tool cutter driving construction including an anchor to engage the pipe, cutters to cut the pipe, and a friction drive between said anchor and cutters including a plurality of friction rings, a drive sleeve to be moved longitudinally by said rings to cause advance of the cutters, and means to adjust the frictional pressure on said rings, including a spring.

9. An outside pipe-cutting tool cutter driving construction including an anchor to engage the pipe, cutters to cut the pipe, and a friction drive between said anchor and cutters including a plurality of friction rings, a drive sleeve to be moved longitudinally by said rings to cause advance of the cutters, and means to adjust the frictional pressure on said rings, including a spring and means to adjust the pressure of said spring against the rings.

10. An outside pipe-cutting tool cutter driving construction including an anchor to engage the pipe, cutters to cut the pipe, and a friction drive between said anchor and cutters including a plurality of friction rings, a drive sleeve to be moved longitudinally by said rings to cause advance of the cutters, and means to adjust the frictional pressure on said rings, including a spring and means to adjust the pressure of said spring against the rings while the tool is in use in a well.

11. An outside pipe-cutting tool cutter driving construction including an anchor to engage the pipe, cutters to cut the pipe, and a friction drive between said anchor and cutters including a plurality of friction rings, a drive sleeve to be moved longitudinally by said rings to cause advance of the cutters, and means to adjust the frictional pressure on said rings, said rings having recesses therein to allow the flow of fluid between and around the rings so that such fluid will not affect the frictional pressure on the rings.
